STEAM SYSTEM CONTROL UNIT

Orville A. Hunt and Louin Tiller, Chicago, Ill., assignors, by mesne assignments, to Reconstruction Finance Corporation, Chicago, Ill., a corporation of the United States

Application February 28, 1949, Serial No. 80,802

17 Claims. (Cl. 237—9)

1

Our invention relates to steam systems with special reference to steam systems for drying operations and is directed to improvements on the type of steam system set forth in the Harrison et al. Patent 2,366,322, issued January 2, 1945.

Other copending applications disclosing the subject matter related hereto are: S. N. 78,842, filed February 28, 1949, S. N. 78,605, filed February 26, 1949; S. N. 78,843, filed February 28, 1949; S. N. 78,604, filed February 26, 1949; and S. N. 777,894, filed October 4, 1947.

Our invention refers to heating systems in which steam acting through heat-exchange devices processes some material such as cloth, paper, plastics, or the like, and in which steam also is used to heat some liquid extraneous to the steam system; that is to say, some liquid apart from the make-up water requirements of the steam system itself. The extraneous liquid may, for example, be the water that must be heated for washing clothes in a steam laundry or may be any other liquid in any other industry where a steam system is used for processing.

The general object of our invention is to achieve greater efficiency and economy in a steam system such as described and, more specifically stated, is to do so by means involving the transfer of heat to the extraneous liquid.

The preferred practices of our invention employ a release valve at the end of the return line to draw a fraction of the steam all the way through the system to create velocity in the system as well as to sweep condensate out of the equipment back to the boiler room. For overall economy, this fraction of steam that is drawn from the return line may be used to preheat make-up water for the system.

Whenever the make-up water demand of a steam system appears to be especially low because the natural losses from the system are exceptionally low, the amount of steam that must be released to create optimum velocity may be more than can be consumed by the available relatively small quantity of make-up water.

The present invention contemplates meeting this situation by using the extraneous liquid to consume heat from the return end of the clear channel system in such a way as to set up whatever velocity is desirable without waste of released steam. The transfer of heat to the extraneous liquid may be direct or indirect, and the heat may be taken either from the return line above the release valve or from the released fluid on the discharge side of the valve.

Two different practices of the invention are

2

described by way of example. In the first practice of the invention, heat is taken from the return line above the release valve. The extraneous liquid is employed to condense steam either directly or indirectly, thereby creating velocity in the system and to that extent reducing the need for releasing velocity-promoting steam from the end of the system. Thus without sacrificing velocity, the amount of steam released may be reduced to the actual amount needed to preheat and deaerate the make-up water for the boiler. In the second practice of the invention, heat is transferred from the released steam to the extraneous liquid, preferably by indirect methods. 15 In this manner any steam released from the system in excess of the requirements for preheating make-up water may be completely consumed in raising the temperature of the extraneous liquid.

The various objects and advantages of the invention will be apparent from the following detailed description taken with accompanying drawings.

In the drawings, which are to be regarded as merely illustrative:

25 Fig. 1 is a diagram of a typical laundry steam system incorporating one form of the new unit; and

Fig. 2 is a similar diagram illustrating another practice of the invention.

30 For the purpose of disclosure and to illustrate the principles involved, the present disclosure will be directed to a steam system for a laundry, but it will be clear to those skilled in the art that the invention is applicable to many different fields.

35 Fig. 1 illustrates how the invention may be embodied in a piece of apparatus that may be manufactured as a self-contained unit for installation in steam plants, usually in the boiler room. This form of the unit includes an upright tank or receiver 10 and a housing or casing associated therewith.

40 Fig. 1 shows six pipes connected to the master control unit. These six pipes are: an inflow pipe 12 for conducting to the unit the so-called extraneous liquid which the steam system heats in addition to carrying out its primary function of drying clothes; an outflow pipe 13 for carrying the extraneous liquid away from the unit; an inflow pipe 15 for supplying new water to the unit to be used for make-up for the boiler in the steam system; an inflow pipe 16 connected to the discharge side of the usual boiler feed pump; an outflow pipe 17 which is the boiler feed line for supplying water to the boiler; an inflow pipe 18 which

is the return line of the steam system; and at a lower level, an outflow pipe 20 that is connected to the intake side of the boiler feed pump. If desired, an additional vent pipe 21 may be connected to the vent opening of the tank 10.

Fig. 1 shows diagrammatically the principal elements of a steam system including the important parts of the new master control unit. The parts of the unit itself are shown inside a rectangle 22 indicated by a broken line. Everything inside this rectangle is inside the casing of the unit.

In the system shown in Fig. 1, steam from a boiler 23 is supplied through a header 25 to a plurality of equipment heat exchangers or steam-using devices 26. Such devices may be, for example, the various machines in a laundry or the drying equipment used in paper manufacture, plastics, etc. Return pipes 27 from the various pieces of equipment connect with the previously mentioned return line 18.

Instead of traps, each of the return lines 27 is provided with a suitable restriction such as a nipple 28 of a relatively small diameter. It will be noted that in such an arrangement there is open communication from the return line 18 back through the various pieces of equipment 26 to the boiler 23 so that lowering the pressure in the return line 18 will cause flow velocity responses in each of the steam-using devices. In other words, the various pieces of equipment and the return line form a continuously clear channel from the boiler for continuous flow-promoting pressure communication through the system and through the equipment.

The return line 18 is terminally connected to the side of a steam separator 31 which preferably, but not necessarily, also serves as a heat exchanger for using the returned condensate to heat new make-up water. The combined heat exchanger and separator 31 is shaped and dimensioned to permit the condensate to separate from the steam and, if desired, suitable baffles 32 may be added to facilitate such separation.

The condensate that is separated from the steam gravitates through a pipe 33 to the intake side of a condensate pump 35 that is included in the working parts of the master control unit. The pump 35 discharges the condensate upward through a pipe 36. Preferably, the pump 35 operates continuously.

A valve 37 is provided in the pipe 33 to cut the heat exchanger off from the pump if desired. When the valve 37 is closed, all of the condensate and steam that reaches the heat exchanger 31 must flow from the heat exchanger through a pipe 38. The pipe 38 conducts fluid from the return line 18 into the receiver tank 10.

The pipe 38 leads to a two-stage combined heater and mixer 40 which in turn communicates with a spray head 41. Flow through the pipe 38 into the tank 10 is controlled by a thermostatic valve 42 having a thermostat bulb 43 extending into the spray head 41. The thermostat control is such that the valve 42 opens in response to decrease in temperature of the thermostat bulb 43 and closes in response to increasing temperature of the bulb. The critical temperature at which the thermostatic valve 42 opens and closes may be varied by virtue of a manual adjustment 45 on the valve.

The steam or steam mixed with condensate that flows through the pipe 38 and the valve 42

enters a central upright passage 46 in the two-stage heater 40 and divides, one portion flowing into an upper jet 47 for the first-stage heating of new water, and the other portion flowing into a lower jet 48 for the second-stage heating. The upper jet 47 is directed into a Venturi throat 50 and the lower jet 48 is directed into a corresponding Venturi throat 51, each jet and throat forming a low pressure space for the introduction of fluid.

New water for the steam system supplied by the previously mentioned pipe 15 passes through a float-controlled valve 52 and enters the two-stage heater 40 in the low pressure space between the first jet 47 and the Venturi throat 50. The resulting mixture flows through a lateral connecting passage 56 into the low pressure space between the second jet 48 and second Venturi throat 51, where it is joined by the second portion of hot fluid from the pipe 38. From the two-stage heater the heated water flows into the spray head 41 in heat-exchange relation with the thermostatic bulb 43. The water is not only heated but is also under considerable pressure in the spray head 41 and is discharged downwardly through the spray ports with considerable violence.

Preferably the tank 10 is maintained slightly above atmospheric pressure, say, 3 or 4 pounds above atmospheric pressure. For this purpose, the tank is of closed construction and the vent 21 is provided with both a vent valve 58 and a relief valve 59. The vent valve 58 may be adjusted at a slightly open position to maintain the desired pressure in the tank of 3 or 4 pounds per square inch, and the relief valve 59 may be adjusted to pop off at, say, 8 to 10 pounds per square inch.

It is contemplated that the spray capacity of the spray head 41 will be so limited relative to the input of fluid that the pressure in the spray head will rise above the pressure prevailing in the tank 10 when the thermostatic valve 42 is open. Under such conditions, the pressure in the spray head may go substantially above the tank pressure. It is further contemplated that the extent to which pressure will rise in the spray head under given conditions may be varied either by varying the number of spray openings or by changing the size of the spray openings.

When the heated water is released in fine droplets from the spray head 41 into the interior of the tank 10, the droplets are shattered by flashing action and the non-condensable gases are effectively released from the water to escape upwardly through the tank vent. A vent condenser 80 in the upper part of the tank not only reclaims heat from the escaping gases but also condenses any steam that may tend to escape with the gases, the recovered condensate dripping to the bottom of the tank.

The tank contains in its lower portion a reserve body 60 of deaerated make-up water supplied by the above-described spray action. When the level of this body drops, a suitable float 61 opens the previously mentioned valve 52 by suitable mechanical means including an upwardly extending operating rod 62. If the level of the water body 60 rises too high, it overflows through an overflow pipe 63. To prevent the release of pressure through the overflow pipe 63, it is provided with a float valve 64 that is normally closed but opens automatically whenever the water level in the tank rises unduly. When desired, the

whole water content of the tank may be flushed out by opening a drain valve 66.

The deaerated make-up water in the tank 10, usually at above 212° F. because of the pressure in the tank, is taken from the tank through the previously mentioned pipe 20 to the intake side of the usual boiler feed pump 67 and is discharged by the pump into the previously mentioned pipe 16. The pipe 16 is connected to the inlet end of a heat-exchange coil 68 in the previously mentioned combined heat exchanger and steam separator 31. The outlet end of this coil 68 is joined to the previously mentioned pipe 36 leading to the boiler feed line 17.

The feed water pump 67 may be controlled in a well-known manner by means responsive to changes in the water level in the boiler 23 or in some practices of the invention may be manually adjusted to run continuously at approximately the rate required to keep the boiler level constant. In either event, the float 61 in the master control tank 10 will drop to cause new water to be supplied to the system in accord with the boiler demand.

The previously mentioned outflow pipe 13 from the master control unit leads to the closed water tank 124 for supplying the wash water required in the laundry. This wash water is the so-called extraneous liquid heated by the steam system, meaning that it is not make-up water required by the steam system itself. The make-up water is supplied solely through the previously mentioned inflow pipe 15.

The pipe 13 may supply all of the wash water to the tank 124 or may supply any proportion of the total demand, and as will be explained, preferably the master control unit provides means whereby any desired proportion of the flow through pipes 12 and 13 may, in effect, be bypassed around the unit.

Water in the tank 124 is heated by suitable means such as a steam coil 123 supplied by a pipe 125 from the previously mentioned steam header 25. Steam entering the coil 123 may be controlled in a well-known manner by a thermostatic valve 126 responsive to temperature changes in the tank. Condensate forming in the coils 123 is preferably delivered through a restriction 81 into a return pipe 82 leading to the previously mentioned return line 18.

In a typical laundry as much as half of the total steam consumption is required for heating the wash water, but in the system here described, all of the condensate so formed is kept in a closed pipe system and returned in toto to the boiler room. It will be apparent to those skilled in the art that a steam system of this character may have an exceptionally low demand for make-up water. On the other hand, if the release valve 42 is relied upon entirely to maintain the most effective flow velocity in the system, it may be necessary to release a relatively large quantity of steam, much larger than can be utilized in preheating the make-up water inside the master control unit. This is the problem to which the present invention is directed.

In Fig. 1 this problem is solved by the following arrangement for utilizing the cooling effect of the extraneous liquid.

As heretofore mentioned, the wash water supply, or at least a portion of the total supply, enters the master control unit by pipe 12 and leaves by pipe 13. Inside the unit the two pipes 12 and 13 are preferably directly interconnected by a

pipe 85 having two spaced manually operated valves 86 and 87.

On the upstream side of the valve 86, a pipe 88 extends from the pipe 85 to the inlet of the previously mentioned vent condenser 80. Flow to the vent condenser may be controlled by a suitable valve 90. From the outlet of the vent condenser a pipe 91 controlled by a valve 92 connects with the pipe 85 between the two valves 86 and 87. Branching from the pipe 91 is a pipe 93 controlled by a valve 95. This pipe 93 connects with the inlet of a second heat-exchange coil 96 in the separator 30 and the outlet of the coil is connected by a pipe 97 with the previously mentioned pipe 85 downstream from the valve 87.

Operation

The manner in which the described system operates may readily be understood from the foregoing description. The adjustment 45 of the thermostatic valve 42 is set at a temperature high enough to release steam from the end of the system in sufficient quantity to keep the pressure in the return line 18 substantially below the pressure of the steam supplied to the pieces of laundry-drying equipment 26. As a result, there is continuous flow of steam into and through the pieces of equipment to the return line 18. The fraction of steam that passes beyond the equipment is thoroughly intermixed with the condensate in the restrictions 28, thereby entraining the condensate for conveyance through the return line 18 to the end of the system.

In a steam system having approximately 100 pounds per square inch gauge pressure in the spray header 25, the setting of the thermostatic valve may be, for example, somewhat above 230° F. In any event, the temperature setting will be above the normal temperature prevailing inside the tank 10. If the tank 10 has a pressure, say, 4 to 6 pounds gauge, the temperature in the tank will be in the range of 224°-230° F.

Since the temperature of the master control tank is below the temperature setting of the thermostatic valve, the tank tends to cool the thermostatic bulb 43 for opening action of the valve 42. Whenever the bulb 42 opens, however, the high-temperature fluid released from the separator 31 again heats the thermostat to cause closing action of the valve.

Since a temperature above 230° F. cannot be attained in the spray head 41 as long as the spray head interior is at the same pressure as the interior of the tank 10, the initial flow of steam from the thermostatic valve or the initial flash of steam by flash action from condensate released through the valve does not have a temperature above 230° F. The restrictive action 60 of the spray openings, however, is effective to cause rising back pressure in the spray header. The temperature in the spray header rises correspondingly and soon climbs above the temperature setting of the thermostatic valve. It is apparent then that the flow passage from the thermostatic valve 42 to the discharge openings of the spray header 41 functions as a pressure accumulation space to make possible a relatively high temperature required for valve control as well as for the deaeration of make-up water.

Whenever new make-up water is required, the float 51 lowers to open the water valve 52, and the consequent flow of water into the two-stage mixer 40 cools the thermostatic bulb 43 for opening action of the valve.

In the usual method of operation, the flow of new water is adequate to keep the thermostatic valve open in opposition to the heating effect of the fluid from the return line so that the thermostatic valve stays open as long as the flow of new water continues.

The function of the vent condenser 80 is to condense steam inside the tank 10, thereby lowering the tank pressure and temperature. The resultant cooling action on the thermostatic bulb 43 causes opening action of the valve 42. Thus, the vent condenser inside the pressure tank 10 supplements the cooling action of new make-up water to increase the amount of fluid released from the return end of the system. At the same time, the condensing action of the vent condenser salvages the heat content of the released steam.

In the preferred mode of operation, water from the inflow pipe 12 flows through the vent condenser 80 and the heat-exchange coil 96 in series, the valves 86, 87, and 92 being closed and the valves 90 and 95 being open. The water flowing into the coil 96 has been preheated by the vent condenser 80 but is nevertheless far below the temperature of steam in the separator 31. As a result, the flow of water through the coil 96 causes steam to condense in the separator and, of course, such condensation lowers the pressure at the end of the return line to promote steam flow through the system.

It is apparent that the make-up water entering the master control unit to cool the thermostatic bulb 43 accounts for only part of the total velocity created in the system and consumes only a part of the steam that reaches the end of the system. The vent condenser 90 accounts for additional velocity by its cooling effect on the thermostatic bulb and condensation of steam inside the tank. Finally, the condensing action of the coil 96 accounts for the rest of the total velocity and consumes the rest of the steam that reaches the end of the return line.

Upon analysis it is seen that B. t. u.'s are transferred from the end of the return line of the steam system to the wash water for preheating of the wash water, and since a very large quantity of wash water is consumed in laundry operations, as many B. t. u.'s may be transferred as may be needed to reach whatever velocity level is found desirable in the steam system.

While in the described practice of the invention both the vent condenser 80 and the steam-condensing coil 96 are used, obviously either may be used alone. To use the vent condenser 80 alone, valves 86 and 95 are closed and valves 87, 90, and 92 are open. To use the coil 96 in the separator 31 alone, valves 90 and 87 are closed and valves 86, 92, and 95 are open.

The thermostatic valve 42 may completely close or only nearly close in response to rising temperature, and the valve may be either a quick-acting valve or a slow-acting valve. If a slow-acting valve is used, it will tend to stay open at an equilibrium position in the absence of make-up water flow with the released steam condensed by the vent condenser 80. Whenever new make-up water is admitted through the pipe 15, the valve will merely open wider.

Only high-temperature water reaches the boiler 23 because, in the first place, the condensate that is returned directly to the boiler by the pump 35 is not permitted to drop to atmospheric pressure, and, in the second place, all new water added to the system is effectively preheated. In a system using steam at 100 pounds per square inch gauge,

the condensate discharged by the pump 35 will be well above 300° F. The new deaerated water, already preheated to above 212°, is further heated under pressure in the coil 68 before intermixing with the condensate in the pipe 36, so that the final mixture of condensate and make-up water usually reaches the boiler at above 300° F.

The second form of the invention

The second form of the invention shown in Fig. 2 is, in large part, similar to Fig. 1, as indicated by the use of corresponding numerals to indicate corresponding parts.

One difference is that a vent condenser 53 cooled by make-up water is used instead of the previously described vent condenser 80 cooled by the extraneous liquid. Cold make-up water from the inflow pipe 15 flows into the vent condenser 53 under control of the previously mentioned float valve 52, and from the vent condenser flows through a pipe 55 to the two-stage heater 49.

A second difference is that the separator 31 at the end of the return line has only one heat-exchange coil, a coil 69 that serves the same function as the previously mentioned coil 68 and is connected in substantially the same manner to the pipes 16 and 36.

In the second form of the invention, B. t. u.'s are transferred from the end of the return line of the system to the wash water in the tank 124 by the following arrangement. The wash water in the tank 124 is heated by the steam coil 123 in the usual manner, but in this instance the returns from the steam coil drain into a trap 122. The condensate from the trap 122 passes through a coil 118 in a heat exchanger 119 and then is carried by a pipe 14 to the previously mentioned pipe 55 in the master control unit. All or a part of the wash water supplied to the tank 124 flows from a supply pipe 120 into the heat exchanger 119 to cool the coil 118 and then flows through a pipe 121 into the tank 124.

The heat exchanger 119 is shown as positioned outside the cabinet or casing of the master control unit represented by the rectangle 22 but in some practices of the invention may be inside the cabinet.

In the second form of the invention the pre-heating of the make-up water in the heat exchanger 119 cools the condensate delivered to the pipe 14 substantially below the temperature setting of the thermostatic valve 42. As a result, the precooled condensate reaching the two-stage mixer through the pipe 55 causes the thermostatic valve 42 to open and then condenses the steam released by the valve. Thus, the make-up water flowing to the tank 124 through the heat exchanger 119 takes B. t. u.'s from the condensate passing through the heat exchanger, and the cooled condensate in turn takes B. t. u.'s from the end of the return line. The net result is that B. t. u.'s are transferred from the return end of the system to the wash water tank 124, just as in the first described form of the invention, notwithstanding the fact that in this second instance the wash water itself does not come directly into heat-exchange relation with the return end of the system.

It is apparent that both of the described embodiments of the invention solve the problem of creating adequate velocity in a "clear channel" steam system that has an exceptionally low demand for make-up water, and that both embodiments apply the same principle of transferring

B. t. u.'s from the return line of the system to the extraneous liquid that is heated by the system.

Our description in detail of preferred practices of the invention, for the purposes of disclosure and to illustrate the principles involved, will suggest to those skilled in the art various changes and substitutions under our basic concepts. We reserve the right to all such departures from our disclosure that fall within the scope of our appended claims.

We claim as our invention:

1. In a steam system for processing material and additionally supplying heat for a liquid apart from the make-up water demand of the system, said system having a boiler, at least one steam-using device for processing material and a return line on the low pressure side of the device, said device and return line forming a clear channel from said boiler for flow-promoting pressure communication through the system, the combination therewith of means to promote steam flow through said device, said means including: a receiver connected with said return line, said receiver being under substantially less pressure than the return line, a valve for releasing fluid from said return line into said receiver to promote flow in the system, means to cause opening action of the valve in response to lowering of the pressure-temperature condition in said receiver and vice versa, a heat exchanger to cool the interior of said receiver with make-up water thereby to favor opening action of said valve for creating flow in the system, and means for preheating at least a portion of said liquid by fluid in said return line of the system with consequent condensing action in the return line for further promotion of flow in the system.

2. In a steam system for processing material and additionally supplying heat for a liquid apart from the make-up water demand of the system, said system having a boiler, at least one steam-using device for processing material and a return line on the low pressure side of the device, said device and return line forming a clear channel from said boiler for flow-promoting pressure communication through the system, the combination therewith of means to promote steam flow through said device, said means including: a receiver connected with said return line, said receiver being under substantially less pressure than the return line, a valve for releasing fluid from said return line into said receiver to promote flow in the system, means to cause opening action of the valve in response to lowering of the temperature in said receiver and vice versa, a heat exchanger to cool the interior of said receiver with make-up water thereby to favor opening action of said valve for creating flow in the system, and means for preheating at least a portion of said liquid by fluid in said return line of the system with consequent condensing action in the return line for further promotion of flow in the system.

3. In a steam system for processing material and additionally supplying heat to a liquid apart from the make-up water demand of the system, said system having a boiler, at least one steam-using device for processing material and a return line on the low pressure side of the device, said return line being closed from the action of atmospheric pressure so as to create back pressure substantially above atmospheric pressure and comparable to the boiler pressure with corresponding high temperature in the return line, said device and return line forming a continuously clear channel from said boiler for continu-

ous flow-promoting pressure communication through the system, the combination therewith of means including a heat exchanger in the return line and a conduit conducting said liquid to the heat exchanger for transferring B. t. u.'s from said return line to said liquid, thereby to condense steam in the return line for creating flow through said channel and steam-using device.

4. In a steam system for processing material and additionally supplying heat for a liquid apart from the make-up water demand of the system, said system having a boiler, at least one steam-using device for processing material and a return line on the low pressure side of the device, said device and return line forming a clear channel from said boiler for flow-promoting pressure communication through the system, the combination therewith of means to promote steam flow through said device, said means including: a valve to release fluid from said return line into a region of substantially lower pressure to promote flow in the system, a thermostat for causing opening operation of said valve in response to temperature below a given temperature and closing operation of the valve in response to temperature above said given temperature, said thermostat being positioned to be heated by the fluid discharge of the valve, means to direct make-up water into mixture with said discharge of the valve for cooling effect on said thermostat, a heat exchanger in said steam system for heating said liquid, means to convey the cooled condensate from said heat exchanger into mixture with said discharge of the valve for cooling effect on said thermostat, and means to deliver said mixture to said boiler.

5. In a steam system for processing material and additionally supplying heat for a liquid apart from the make-up water demand of the system, said system having a boiler, at least one steam-using device for processing material and a return line on the low pressure side of the device, said device and return line forming a clear channel from said boiler for flow-promoting pressure communication through the system, the combination therewith of means to promote steam flow through said device, said means including: a valve to release fluid from said return line into a region of substantially lower pressure to promote flow in the system, a thermostat for causing opening operation of said valve in response to temperature below a given temperature and closing operation of the valve in response to temperature above said given temperature, said thermostat being positioned to be heated by the fluid discharge of the valve, means to direct make-up water into mixture with said discharge of the valve for cooling effect on said thermostat, a heat exchanger supplied with steam from the system for heating said liquid, a second heat exchanger in the system supplied with condensate from said first heat exchanger to preheat said liquid thereby cooling the condensate below said given temperature, and means to convey the cooled temperature from said second heat exchanger to said thermostat for causing opening operation of said valve.

6. In a steam system for processing material and additionally supplying heat for a liquid apart from the make-up water demand of the system, said system having a boiler, at least one steam-using device for processing material and a return line on the low pressure side of the device, said device and return line forming a clear channel from said boiler for flow-promoting pressure

11

communication through the system, the combination therewith of means to promote steam flow through said device, said means including: a valve to release fluid from said return line into a region of substantially lower pressure to promote flow in the system, a thermostat for causing opening operation of said valve in response to temperature below a given temperature and closing operation of the valve in response to temperature above said given temperature, said thermostat being positioned to be heated by the fluid discharge of the valve, means to direct make-up water into heat-exchange relation with said thermostat for opening action of said valve in response to the demand of the system for water, and means to pass a stream of said liquid in heat-exchange relation with the fluid in said return line above said valve whereby the liquid is pre-heated and condensing action occurs above the valve to supplement the velocity-creating effect of the opening action of the valve.

7. In a steam system for processing material and additionally supplying heat for a liquid apart from the make-up water demand of the system, said system having a boiler, at least one steam-using device for processing material and a return line on the low pressure side of the device, said device and return line forming a clear channel from said boiler for flow-promoting pressure communication through the system, the combination therewith of means to promote steam flow through said device, said means including: a valve to release fluid from said return line into a region of substantially lower pressure to promote flow in the system, a thermostat for causing opening operation of said valve in response to temperature below a given temperature and closing operation of the valve in response to temperature above said given temperature, said thermostat being positioned to be heated by the fluid discharge of the valve, means to direct make-up water into heat-exchange relation with said thermostat for opening action of said valve in response to the demand of the system for water, a heat exchanger included in said return line for preheating at least a portion of said liquid and thereby condensing steam in the return line to supplement the flow-promoting effect of the opening action of said valve, a second heat exchanger supplied with fluid from said system for heating said liquid, means to return the condensate from said second heat exchanger to supply boiler feedwater for the system, and means to pass at least a portion of said liquid through said first heat exchanger and then through the second heat exchanger.

8. In a steam system for processing material and additionally supplying heat for a liquid apart from the make-up water demand of the system, said system having a boiler, at least one steam-using device for processing material and a return line on the low pressure side of the device, said device and return line forming a clear channel from said boiler for flow-promoting pressure communication through the system, the combination therewith of means to promote steam flow through said device, said means including: a receiver connected with said return line, said receiver being under substantially less pressure than the return line, a valve to release fluid from said return line into said receiver, a thermostat for causing opening operation of said valve in response to temperature below a given temperature and closing operation of the valve in response to temperature above said given tem-

12

perature, said thermostat being positioned to be heated by the fluid discharge of the valve and to respond to temperature changes in said receiver, a heat exchanger in said receiver for cooling the interior of the receiver to favor opening action of said valve, and means to direct a stream of said liquid through said heat exchanger for preheating the liquid and cooling the interior of the receiver.

10. In a steam system, a combination as set forth in claim 8, which includes means to direct make-up water into heat-exchange relation with said thermostat for opening action of said valve in response to demand of the system for water.

15. In a steam system for processing material and additionally supplying heat for a liquid apart from the make-up water demand of the system, said system having a boiler, at least one steam-using device for processing material and a return line on the low pressure side of the device, said device and return line forming a clear channel from said boiler for flow-promoting pressure communication through the system, the combination therewith of means to promote steam

20. flow through said device, said means including: a valve to release fluid from said return line into a region of substantially lower pressure for creating velocity in the system, a heat exchanger for cooling the contents of said return line for causing condensation therein to create additional velocity in the system, and means to direct a stream of said liquid through said heat exchanger.

25. 11. In a steam system, a combination as set forth in claim 10, which includes a pump in communication with said return line to convey condensate from said return line to said boiler.

30. 12. In a steam system for processing material and additionally supplying heat for a liquid apart from the make-up water demand of the system, said system having a boiler, at least one steam-using device for processing material, and a return line on the low-pressure side of the device, said device and return line forming a clear channel from said boiler for flow-promoting pressure

35. communication through the system, the combination therewith of means to promote steam flow through said device, said means including: means to bring said liquid into heat-exchange relation with condensate apart from said return line, thereby to raise the temperature of said liquid and at the same time cool said condensate below the temperature prevailing in said return line, and means to bring said condensate into heat-exchange relation with steam that reaches the end of the system through said return line, thereby heating the condensate and at the same time condensing at least a portion of said steam.

40. 13. A steam system as set forth in claim 12, in which said means for bringing condensate into heat-exchange relation with steam intermixes the condensate and steam.

45. 14. In steam system for processing material and additionally supplying heat for a liquid apart from the make-up water demand of the system, said system having a boiler, at least one steam-using device for processing material, and a return line on the low-pressure side of the device, said device and return line forming a clear channel from said boiler for flow-promoting pressure communication through the system, the combination therewith of means to promote steam flow through said device, said means including: means to bring said liquid into heat-

50. exchange relation with condensate apart from

said return line, thereby to heat said liquid and simultaneously cool said condensate below the temperature prevailing in said return line, means to release steam from said return line, thereby to lower pressure therein for promoting flow through the system, and means to bring said released steam into heat-exchange relation with said cooled condensate, thereby to condense the steam and simultaneously reheat the condensate.

15. In a steam system for processing material and additionally supplying heat for a liquid apart from the make-up water demand of the system, said system having a boiler, at least one steam-using device for processing material, and a return line on the low-pressure side of the device, said device and return line forming a clear channel from said boiler for flow-promoting pressure communication through the system, the combination therewith of means to promote steam flow through said device, said means including: a first heat exchanger utilizing steam from the system to heat said liquid, a second heat exchanger utilizing condensate from the first heat exchanger to preheat said liquid, thereby cooling the condensate below the temperature prevailing in said return line, and means to bring the cooled condensate from said second heat exchanger into heat-exchange relation with steam that reaches the end of the system through said return line, thereby to reheat the condensate and at the same time condense at least a part of said steam.

16. In a steam system for processing material and additionally supplying heat for a liquid apart from the make-up water demand of the system, said system having a boiler, at least one steam-using device for processing material, and a return line on the low-pressure side of the device, said device and return line forming a clear channel for said boiler for flow-promoting pressure communication through the system, the combination therewith of means to promote steam

flow through said device, said means including: a first heat exchanger utilizing steam from the system to heat said liquid, a second heat exchanger utilizing condensate from the first heat exchanger to preheat said liquid, thereby cooling the condensate below the temperature prevailing in said return line, means to release steam from said return line, thereby to lower the pressure therein for promoting flow through the

5 system, and means to bring the released steam into heat-exchange relation with the cooled condensate from said second heat exchanger, thereby to reheat the condensate and at the same time to condense at least a part of said released steam.

10 17. In a steam system for processing material and additionally supplying heat for a liquid apart from the make-up water demand of the system, said system having a boiler, at least one steam-using device for processing material and a return line on the low pressure side of the device, said device and return line forming a clear channel from said boiler for flow-promoting pressure communication through the system, the combination therewith of means including a heat exchanger for transferring B. t. u.'s from said return line to said liquid, thereby to heat the liquid and transform steam in the return line into condensate, and means to deliver the condensate 25 30 from the return line direct to the boiler under sustained pressure.
